HEAT EXCHANGER FOR CONTINUOUS TREATMENT OF FLUENT MATERIAL

John E. Laschinger, Bramley, Johannesburg,
Union of South Africa

Original application March 27, 1945, Serial No. 585,113, now Patent No. 2,551,748, dated May 8, 1951. Divided and this application April 6, 1951, Serial No. 219,667

Claims priority, application Union of South Africa September 29, 1944

7 Claims. (Cl. 257—88)

1

This application is a division of the application Serial Number 585,113 filed on 27 March 1945, now Patent No. 2,551,748, patented May 8, 1951.

This invention relates to heat exchangers for continuously effecting heat exchange to or from a stream of material that is fluent in bulk; such as liquids, or granular or particulate solid material or material in which the characteristics of a liquid are more highly developed.

The object of the invention is to approximate closely to the condition that every small element of the stream is equally exposed to the heat exchanging influence for an equal period of time, and thereby to produce a product of a homogeneous character throughout, notwithstanding that the material, for instance Vermiculite undergoing expansion, is sensitive to both temperature and time of heating. The attainment of this object is promoted by subdividing the stream into small batches which are passed through the heat exchanger successively and in isolation from one another and in equal time periods; and by frequently agitating the contents of each batch in a manner calculated to give all its small elements equal exposure to the heat exchanging influence.

Other objects and advantages of the invention will be apparent from the description of an embodiment of the invention, as applied to the heating of material, which follows, and which is illustrated in the accompanying drawings in which

Figure I is an elevation, partly in section, of a furnace according to the invention;

Figure II is a perspective view of the internal arrangement of the furnace, part of the drum wall being broken away;

Figure III is a vertical section of one compartment taken on the line III—III of Figure II;

Figure IV is a vertical section on the line IV—IV of Figure II showing the drum in a different rotational position;

Figure V is a detail in perspective of a modified form of partition;

Figure Va is a further detail in perspective of a modified form of partition; and

Figure VI is a section on the line VI—VI of Figure III.

In the drawings, 2 indicates a drum barrel positioned with its axis 3 horizontal. The drum is provided with circular treads 4 rotatably supported on rollers 5. The drum is rotated constantly in one direction by driving means 6.

2

The barrel of the drum is enclosed within a furnace casing 7, which may be heated in any convenient manner, for instance by fuel burnt at 8 in the lower part of the casing. Products of combustion pass away through the chimney 9.

It will be understood that in an apparatus designed to extract heat from the material being heated, the burner 8 would be omitted and suitable cooling means would be substituted for it, such for instance as a cold air blast directed on to the drum or a cooling coil surrounding the drum, or a cooling medium fed into the drum cavity.

The fluent material to be subjected to treatment with or without an addition of powdered or granular fuel is fed by a launder 10 to a batch-making section 11 of the drum at the feed end 12 thereof; and the treated material is gravitationally discharged from the delivery end 13 of the drum to a receiver 14. 15 represents a number of partitions extending in planes materially transverse to the axis 3 and spaced along the length of the drum, and defining a series of compartments 16, 16^u, 16ⁱⁱ, 16^v, 16^v, 16ⁱⁱ, of which the compartment 16ⁱⁱ constitutes the batch-making compartment identified as 11 in Figure I. The partitions may be parallel, or depart from parallelism where this may be desirable owing to the nature of the material being treated or the kind of treatment being carried out.

The partitions 15 may be flat, as shown in Figures I and II; or they may be dished as shown in Figure V. In either case the central area of each partition 15 may be cut away at 17, so that the interior of the drum is open. An end view therefore shows an open axial channel extending completely through the drum, which channel is useful for such purposes as passing off moisture, vaporised or fumes produced when the material is heated; for visual inspection of the material in the drum; if desired, for the introduction of heating or cooling gas and for accommodating a radiating or absorbing element; or for passage of a stream of gas or liquid for the removal of products of decomposition (i.e. gas or liquid); and to reduce the partial pressure of such reaction products with the object of increasing or controlling the reaction rate.

Each compartment 16, 16^u, 16ⁱⁱ, 16^v, 16^v, 16ⁱⁱ is made of 360° circumferential extent; so that the batches of material are kept in gravitational contact with the drum wall for long periods between the cascading steps, while the material is subjected to advantageous agitation by the drag of the relatively moving drum wall, which may

be corrugated circumferentially or longitudinally for structural reasons and/or to increase area and agitation.

The circumferential extent of each compartment is defined by cross partitions 18 that spring from the drum wall at 19 and extend in the axial direction between the boundary walls 15 of each compartment. The movement of each compartment is orbital in the sense that every portion of it moves orbitally. The phase displacement between successive compartments may be 180° as shown, or such other angle as may be selected as suitable.

The cross partitions 18 also form, with the walls 15, a scoop formation at the trailing end of each compartment. Batch transfer from one compartment to the next is effected by the combination of the scoop formation with a plain hole 20 in each compartment wall 15; towards which hole the immediately adjacent portion 21 of the partition 18 is tilted (as shown in Figure VI).

As well as defining the circumferential beginning and end of each compartment, each cross partition 18 also performs the function of a mechanical barrier that maintains separation of a batch circumferentially in front of it, from a batch circumferentially behind it; and moreover allows the latter to gravitate into the place of the former as the drum rotates. To assist in this operation it may be so curved as to be convex above when within the lower half of the drum and concave above when within the upper half of the drum. This is shown in Figure III where the cross partition 18a of compartment 16ⁱⁱ is rising with its concave face 22 upward so that it acts as a scoop to contain and lift a batch a. The batch a has been raised to the position where it begins to pour through the hole 20a in the wall 15 and into compartment 16ⁱⁱⁱ. In there it is falling on the convex and descending face 23 of the cross partition 18b of the next compartment 16ⁱⁱⁱ and thereby being diverted into the pocket 24 formed by the conjunction of 18b with the adjacent wall of the drum. In the pocket 24 the batch a is shielded from the next earlier batch b that is at the same moment lying at the bottom of the drum and under the concave face 22 of the cross partition.

Figure IV shows the two batches a and b in the compartment 16ⁱⁱⁱ after further rotation of the drum through about 30°. Batch b is now being collected at the concave side of partition 18b preparatory to being raised to the position equivalent to that of batch a in Figure III. Batch a is being released from the pocket 24 and spread out on the barrel of the drum, as batch b is in Figure III. To produce this sequence the holes 20 are phased 180° apart; and each batch remains in a compartment during one and a half revolutions of the drum.

In order to give adequate lift it is desirable for the holes 20 to be near the drum barrel 2; which, on the other hand, opens the possibility of batches that are gravitationally lying in the compartments at opposite sides of their common partition 18, becoming mixed with one another when the hole 20 is at the low zone of its orbit, as is 20b in Figure III. To overcome this, the cross partition 18 is continued at 25 around the hole 20; to be convex below when the hole 20 is at the bottom of its orbit; and so that its terminal lip 26 is then and thereafter above the level of the material lying in the bottom of the drum.

It is pointed out that the precise shape of the

cross partitions 18 is selected in relation to the nature of the material being treated and the nature of the treatment itself, as well as to the speed of rotation of the drum and the varying dynamic consequences of rotation at different speeds on the fluidity of the material. Mechanical considerations such as the provision of adequate heat-transfer area and stability of the cross-partition under heating, ease of manufacture, etc., must also be considered. In Figure Va the cross-partition differs from that of the other figures in that it has a leading face 27 which is sloped towards the hole 20 to promote complete gravitational evacuation of the batch of material in the scoop formation through the hole 20.

In operation, material fed in a continuous stream into the compartment 16ⁱ by the launder 10 is batched by the compartment. Each batch in turn is gravitationally discharged into the compartment 16ⁱⁱ through the hole 20; and so on. Isolation of the separate batches is ensured by the means discussed above, the advance of the series of batches being axial and the magnitude of each step of advance being the axial width of the compartments. On discharge from the last compartment each batch in turn is received by the receiver 14.

By keeping the batches small, the time periods of conveyance of their constituent small elements are approximated closely to that of the batches themselves. Each batch, after being received in a compartment, remains on the orbital bottom of the compartment substantially the entire rotation of the latter so that the batch is exposed to quiet heat transfer by contact with the outer wall; and so also that the relative movement between compartment and batch causes a mild agitation of the batch. The interruption of the relatively quiet heat transfer to or from the batches by a succession of falls causes all the small elements of each batch correspondingly to be subject to frequent changes of position in the batch, which is conducive to equalizing their exposure to the heat exchanging influence. At the same time, the importance of isolating the batches lies in preventing the small elements of the batches from escaping from the control that determines their time period and intensity of treatment in the heat exchanger.

I claim:

1. A heat exchanger suitable for continuously treating material that is fluent in bulk, consisting of a rotatable drum the wall of which is impermeable to solids, means to adjust the temperature of the wall to a temperature different from that of the surrounding atmosphere, a series of transverse partitions dividing the drum into a series of axially consecutive separate compartments, means to feed material into the first of the series of compartments and means to receive batches of material discharged from the last of the series of compartments, means defining a single scoop within each compartment, the scoop being adapted to lift material in the compartment during the upward movement of the scoop, and means defining a transfer hole in each partition opening out of the concavity of the scoop which is towards the feed end of the drum, each scoop being arranged for the material it is lifting to cascade gravitationally through the hole opening out from its concavity when the scoop has completed at least a portion of its upward movement, and each scoop being so circumferentially displaced from the scoop in the last preceding compartment as to have started its upward movement

before cascading of material into its compartment commences.

2. The exchanger claimed in claim 1 wherein each scoop includes one of said transverse partitions and a cross-partition in each compartment extending from the drum wall and forming a mechanical barrier to prevent the mingling of a batch of material circumferentially in front of the barrier with a batch circumferentially behind the barrier.

3. The exchanger claimed in claim 2 in which the cross-partitions in successive compartments are phased 180° apart.

4. The exchanger claimed in claim 2 in which each cross-partition is curved to be convex upward when within the lower half of the drum, the convex side forming a pocket with the adjacent wall of the drum, and the concave side delivering material to the transfer hole upon further rotation.

20

5. The exchanger claimed in claim 4 in which the ends of the cross-partitions are curved around the transfer openings to be convex below when the transfer openings are in their lowermost position and so that the terminal lip of each cross-partition is then and thereafter above the level of material lying in the bottom of the drum.

6. The exchanger claimed in claim 1 in which the transverse partitions are dished.

7. The exchanger claimed in claim 1 in which the part of the scoop adjacent the transfer opening is tilted towards the opening.
